AUTOMOBILE LIFT

John H. Halstead, San Jose, Calif.

Application April 9, 1956, Serial No. 576,977

6 Claims. (Cl. 187—8.75)

This invention relates to improvements in automobile lifts that may be used in garages and service stations to lift automobiles and trucks for servicing and repair; and in particular to improved frame lifts having adaptors carrying jacks that may be adjusted to different positions for safely supporting the frames of automobiles and light trucks of various makes and sizes.

A frame lift for automobiles, light trucks and the like, generally comprises a lift frame that carries a plurality of jacks for supporting several points on the automobile or truck frame. Suitable mechanism, usually hydraulic mechanism, is provided to raise and lower the lift frame. When such frame lifts are to be used with automobiles and light trucks of various makes and sizes, the relative positions of the jacks should be adjustable so that they can engage appropriate parts of the vehicle frame for supporting the vehicle safely. Since the vehicle may vary considerably in size and design, the jacks should be adjustable to a considerable variety of positions. Furthermore, these adjustments must be such that they can be made quickly and conveniently.

Accordingly, objects of this invention include the provision of improved automobile lifts with simple, lightweight and easy-to-handle adaptors carrying jacks that may quickly and conveniently be adjusted to a great variety of positions, that are simple and economical to manufacture, and that provide adequate clearance for all vehicles that may be driven over the lift. Other objects and advantages of the invention will appear as the description proceeds.

Briefly stated, in accordance with certain aspects of this invention, an improved frame lift for automobiles, light trucks, and the like, includes an H-shaped lift frame having four horizontal legs. Conventional hydraulic apparatus is provided for raising and lowering the frame. Each leg of the lift frame has horizontally grooved opposite longitudinal edges. Slidably mounted on each leg of the frame there is an improved adaptor including a horizontal lower slide plate having folded longitudinal edges that engage the grooved sides of the leg so that the adaptor can be moved lengthwise with respect to the leg of the H-shaped frame. A horizontal flat rectangular table is rotatively mounted on top of the lower slide plate and is adapted for unlimited rotation relative thereto. A horizontal upper slide plate has folded longitudinal edges that extend around longitudinal edges of the table, so that the upper slide plate is slidably mounted on the table.

An inverted horizontal slide channel is welded to the top of the upper slide plate, and a jack is attached to this channel by means of a pin so that the jack can be moved either to a horizontal position or to an upright position, selectively. Thus, four jacks are provided that are independently movable longitudinally, transversely, and rotatively with respect to the lift frame. When the jacks are in horizontal positions they lie

2

relatively close to the frame and provide adequate clearance for all vehicles that may be driven over the frame. The construction is simple, easy to handle, neat in appearance, and exceptionally rugged.

5 The invention will be better understood from the following detailed description taken in connection with the accompanying drawing, and its scope will be pointed out in the appended claims. In the drawing:

Fig. 1 is a perspective view of an automobile lift embodying principles of this invention, the lift having four adaptors each carrying a jack, the four adaptors being shown in four different positions in Fig. 1;

Fig. 2 is an exploded perspective view of one of the adaptors;

Fig. 3 is a section taken along the line 3—3 of Fig. 2; Fig. 4 is a section taken generally along the line 4—4 of Fig. 3;

Fig. 5 is a section taken generally along the line 5—5 of Fig. 3;

20 Fig. 6 is a section taken along the line 6—6 of Fig. 2; Fig. 7 is a section taken along the line 7—7 of Fig. 6; and

Fig. 8 is a section taken along the line 8—8 of Fig. 6.

Referring now to the drawing, an improved frame lift for automobiles, light trucks and the like has a horizontal H-shaped lift frame 1 with four outwardly extending horizontal legs 2, 3, 4 and 5. The frame may be raised and lowered by means of a conventional hydraulic mechanism including a piston 6 attached to the cross-piece of the H-frame by suitable means such as bolts, 7. Each leg of the frame, leg 4 for example, has a pair of horizontal grooves 8 and 9 in opposite longitudinal sides thereof. Slidably mounted upon respective ones of the four legs there are four identical adaptors that will now be described.

Each adaptor includes a horizontal lower slide plate 10 having opposite longitudinal edges 11 and 12 that are folded downward and inward, as shown. Edges 11 and 12 engage the slots 8 and 9 so that lower slide plate 10 is securely fastened to a leg of H-frame 1, and is slidably along the length of the leg. The adaptor can be removed from the H-frame, if desired, simply by sliding plate 10 off the end of the leg on which it is mounted. A circular aperture 13 extends through the center of lower slide plate 10. A flat circular retaining plate 14 is welded around its outer circumference onto the top of plate 10, and has a smaller circular aperture 15 aligned with aperture 13.

50 A rotative table 16 is a horizontal flat rectangular plate with rounded corners. Two transverse bars 17 and 18 are welded to the underside of table 16 at opposite ends thereof, as shown. A vertical cylindrical post 19 extends rotatively through aperture 15 and a hole in the center of table 16. The bottom end of post 19 has an enlarged head that fits rotatively within aperture 13 of lower slide plate 10. The top end of post 19 is welded to table 16 so that table 16 is securely fastened to lower slide plate 10 but is capable of unlimited rotation relative thereto. Bars 17 and 18 rest on the top of slide plate 10 and support the ends of rotative table 16.

60 A horizontal upper slide plate 20 has opposite longitudinal edges 21 and 22 that are folded downward and inward, as shown. Folded edges 21 and 22 extend around the longitudinal edges of table 16 so that the upper slide plate is securely fastened to and slidably mounted upon the rotative table. Upper slide plate 20 can be removed from table 16 simply by sliding it off one end thereof. Replacement of the upper slide plate on the rotative table is facilitated by the rounded corners of the table. An inverted channel 23 is welded onto the top of upper slide plate 20.

A jack comprises a jack channel 24 and a jack plate 25 welded transverse to one end thereof. The jack channel consists of a central web and two side flanges that extend lengthwise beyond the web at that end of the jack channel opposite to jack plate 25 and form two parallel tongues 26 and 27 disposed on opposite sides of slide channel 23. Jack channel 24 straddles slide channel 23, as shown, and a pin 28 extends through tongues 26 and 27 and through slide channel 23 for attaching the jack to the slide channel. The jack can be rotated about pin 28 through an angle slightly greater than 90 degrees, so that the jack can be moved either to a horizontal position or to an upright position, selectively. In Fig. 1, two of the four jacks are shown in upright positions, while the other two jacks are shown in horizontal positions. When the jacks are upright, the lower end of the web of the jack channel rests upon the top of the slide channel, as is best shown in Fig. 6, for supporting the jack in an upright position with jack plate 25 substantially horizontal.

When the jacks are positioned horizontally, the vertical distance between the bottom of the H-frame and the uppermost portion of the jack is quite small, about 4½ inches, for example, so that adequate clearance is provided for all vehicles that may be driven over the lift. For supporting selected points on the frame of a vehicle, any or all of the four jacks may be raised to their upright positions and the jacks may be moved longitudinally, transversely, and rotatively with respect to the H-frame for adjusting the jacks to desired positions relative to an automobile or light truck of any make or size.

The improved automobile frame lift herein described is extremely flexible and adaptable for use with all automobiles and light trucks. The adaptors are so low that they can be left on the lift frame at all times and provide adequate clearance for all vehicles. They are light in weight and easy to handle. They are of simple and inexpensive construction, yet are rugged and dependable. Furthermore, the lift and adaptors are neat and attractive in appearance, and make "good housekeeping" easier.

It should be understood that this invention in its broader aspects is not limited to the specific embodiment herein illustrated and described, and that the following claims are intended to cover all changes and modifications that do not depart from the true spirit and scope of the invention.

What is claimed is:

1. An adaptor for automobile lifts, comprising a horizontal lower slide plate having opposite longitudinal edges folded downward and inward, said lower slide plate having a circular central aperture, a flat circular retaining plate welded to the top of said lower slide plate, said retaining plate having a smaller circular aperture aligned with said aperture in the lower slide plate, a horizontal flat table with rounded corners, a pair of transverse bars welded to the bottom of said table at opposite ends thereof, a vertical cylindrical post extending rotatively through said aperture in the retaining plate, the upper end of said post being welded to said table and the lower end of said post having an enlarged head fitting rotatively within said aperture in the lower slide plate, a horizontal upper slide plate slidably mounted upon said table, and a jack attached to said upper slide plate.

2. An adaptor for automobile lifts, comprising a lower slide plate, a table rotatively mounted upon said lower slide plate, an upper slide plate slidably mounted upon said table, an inverted horizontal slide channel welded onto the top of said upper slide plate, a jack channel that straddles said slide channel, said jack channel having a web and two side flanges that extend lengthwise beyond one end of said web forming two parallel tongues disposed on opposite sides of said slide channel, a jack plate welded transverse to the other end of said jack channel, and a pin extending through said tongues and

through said slide channel so that said jack channel can be rotated about said pin either to a horizontal position or to an upright position selectively, an end of said web resting upon the top of said slide channel when said jack channel is in its upright position.

3. An adaptor for automobile lifts, comprising a horizontal lower slide plate having opposite longitudinal edges folded downward and inward, said lower slide plate having a circular central aperture, a flat circular retaining plate welded to the top of said lower slide plate, said retaining plate having a smaller circular aperture aligned with said aperture in the lower slide plate, a horizontal flat table with rounded corners, a pair of transverse bars welded to the bottom of said table at opposite ends thereof, a vertical cylindrical post extending rotatively through said aperture in the retaining plate, the upper end of said post being welded to said table and the lower end of said post having an enlarged head fitting rotatively within said aperture in the lower slide plate, whereby said table is securely fastened to said lower slide plate and is capable of unlimited rotation relative thereto, a horizontal upper slide plate having opposite longitudinal edges folded downward and inward, said folded edges of the upper slide plate extending around opposite longitudinal edges of said table so that said upper slide plate is slidably mounted upon said table, an inverted horizontal slide channel welded to the top of said upper slide plate, a jack channel that straddles said slide channel, said jack channel having a web and two side flanges that extend lengthwise beyond one end of said web forming two parallel tongues disposed on opposite sides of said slide channel, a jack plate welded transverse to the other end of said jack channel, and a pin extending through said tongues and

4. An automobile lift, comprising a horizontal H-shaped frame having four horizontal legs, each of said legs having horizontally grooved opposite longitudinal edges, means for raising or lowering said frame, and four adaptors slidably mounted on respective ones of said four legs, each of said adaptors comprising a horizontal lower slide plate having opposite longitudinal edges folded downward and inward, said folded edges of the lower slide plate engaging said grooved edges of a leg of the frame so that said lower slide plate is securely fastened to said frame and is slidably lengthwise thereon, said lower slide plate having a circular central aperture, a flat circular retaining plate welded to the top of said lower slide plate, said retaining plate having a smaller circular aperture aligned with said aperture in the lower slide plate, a horizontal flat table with rounded corners, a pair of transverse bars welded to the bottom of said table at opposite ends thereof, a vertical cylindrical post extending rotatively through said aperture in the retaining plate, the upper end of said post being welded to said table and the lower end of said post having an enlarged head fitting rotatively within said aperture in the lower slide plate, whereby said table is securely fastened to said lower slide plate and is capable of unlimited rotation relative thereto, a horizontal upper slide plate having opposite longitudinal edges folded downward and inward, said folded edges of the upper slide plate extending around opposite longitudinal edges of said table so that said upper slide plate is securely fastened to said table and is slidably mounted thereon, an inverted horizontal slide channel welded onto the top of said upper slide plate, a jack channel that straddles said slide channel, said jack channel having a web and two side flanges that extend lengthwise beyond one end of said web forming two parallel tongues disposed on opposite sides of said slide channel, a jack plate welded transversely to the other end of said jack channel, and a pin extending through said tongues and

said slide channel so that said jack channel can be rotated about said pin either to a horizontal position or to an upright position selectively, an end of said web resting on the top of said slide channel when said jack channel is in an upright position.

5. An adapter for automobile lifts that have a vertically movable frame with a plurality of horizontal legs, comprising a lower slide plate fitting in lengthwise sliding relation upon one of said legs, a flat table mounted upon the top of said lower slide plate substantially parallel and centered relative thereto, an upper slide plate having opposite longitudinal edges folded downward and inward, said upper slide plate fitting slidably over said table with said folded edges extending around and under opposite edges of said table so that said upper slide plate is held substantially parallel to said table and said lower slide plate while being capable of lengthwise sliding motion relative thereto, said upper slide plate being also capable of rotation relative to said lower slide plate in a plane parallel thereto, said upper slide plate being longer than said table and substantially covering and extending beyond the top of said table when fitted thereon, and a jack attached to said upper slide plate, said jack being movable to an upright position and to a reclining position, selectively.

6. An automobile lift, comprising an H-shaped frame having four horizontal legs, each of said legs having horizontally grooved opposite longitudinal edges, a horizontal lower slide plate having opposite longitudinal edges folded downward and inward, said lower slide plate being

20
25
30

slidably mounted upon the top of one of said legs with said folded edges of the lower slide plate slidably engaging said grooved edges of the leg, a flat table mounted on the top of said lower slide plate substantially parallel and centered relative thereto, an upper slide plate having opposite longitudinal edges folded downward and inward, said upper slide plate fitting slidably over said table with said folded edges extending around and under opposite edges of said table so that said upper slide plate is held substantially parallel to said table and said lower slide plate while being capable of lengthwise sliding motion relative thereto, said upper slide plate being also capable of rotation relative to said lower slide plate in a horizontal plane, said upper slide plate being longer than said table and substantially covering and extending beyond the top of said table when fitted thereon, and a jack attached to said upper slide plate, said jack being movable to an upright position and to a reclining position, selectively.
